(57) **CLAIM**

The ornamental design for a motorcycle trunk rear trim, as shown and described.

DESCRIPTION

FIG. 1 is a front perspective view of the motorcycle trunk rear trim of the present invention.

FIG. 2 is a front elevation view thereof.

FIG. 3 is a rear elevation view thereof.

FIG. 4 is a top view thereof.

FIG. 5 is a bottom view thereof; and,

FIG. 6 is a right side view thereof, the left side being a mirror image of the right side.

The rear surface and front surface portions of the motorcycle trunk rear trim shown in broken lines form no part of the claimed design.
